UNITED STATES PATENT OFFICE.

EDWARD M. TERRYBERRY, OF PHILADELPHIA, PENNSYLVANIA.

REED.

1,070,206.

Specification of Letters Patent.

Patented Aug. 12, 1913.

Application filed April 4, 1912. Serial No. 688,393.

To all whom it may concern:

Be it known that I, EDWARD M. TERRYBERRY, a citizen of the United States, residing at Philadelphia, in the county of Philadelphia, State of Pennsylvania, have invented certain new and useful Improvements in Reeds, of which the following is a specification.

This invention relates to improvements 10 in reeds; and it comprises a reed made up of dents of uniform width with a central portion of the dents arranged in the same plane to present a uniform front for beating or packing the filling, and with the portions 15 of alternate dents to each side of such central portion offset with respect to each other and arranged in staggered relation, all as more fully hereinafter set forth and as claimed.

20 The reed of the present invention is particularly adapted for high slayed work, or for weaving fabrics of fine texture. In the weaving of such fabrics the warp threads passing through the reed as it vibrates are 25 subjected to an excessive amount of friction, with the result that the threads tend to fray or lint up in small knots, and sometimes break. In the old straight dent reed where the dents are arranged parallel to each 30 other, this friction is a source of continual trouble. Attempts have been made to overcome this difficulty by the use of reeds made up of straight dents crossing near their center, and also by the use of alternate dents 35 specially machined to present a central even line for beating the fabric; but such reeds are expensive to manufacture, and require a special form of reed frame; also with the central beating line, any misad- 40 justment of the fabric, relative to this central line, results in an imperfect assimilation of the weft threads in the fabric. According to the present invention, these dis- 45 advantages are obviated and a reed pro- duced simple in construction and inexpensive of manufacture.

In the accompanying drawings, Figure 1 shows a front view of the preferred embodiment of the invention; Fig. 2 is an end 50 view of Fig. 1; Fig. 3 shows the individual dents of which the reed of Figs. 1 and 2 is alternately made up; Fig. 4 shows a modified form of offset dent, both separately and as combined with a straight dent; Fig. 5 55 shows still another modified form of the

offset dent; Fig. 6 shows the individual dents of Fig. 5; Fig. 7 shows a modification in the construction of the individual offset dents; Figs. 8 and 9 show still further embodiments of the invention; Fig. 10 is a section on an enlarged scale taken on the line 10—10, Fig. 2; and Fig. 11, a section on an enlarged scale taken on the line 11—11, Fig. 8.

The reed of the present invention is made 65 up of dents of uniform width, and is shown in Figs. 1 to 3 and 10, as made up alternately of straight dents 4, and offset dents 3, these dents being of uniform width and their ends being fastened in the reed frames 70 1 and 2 in any suitable manner. Since the dents are of uniform width, their ends can be brought together the same as in the old straight dent reed, and hence the present reed can be substituted for the old straight 75 dent reed, without modifying the structure of the loom in which the substitution is made. The dents 3 are provided with central portions, 5, in the same plane as the ends of the dents and as the straight dents 80 4, and between the central portions 5 and the ends, the dents are offset slightly more than the width of the individual dents. In the form shown in Figs. 1 to 3 the central portions 5 extend about one quarter of 85 the length of the reed, and are arranged so that the offset portion below this central portion is also about one quarter of the length of the reed, and the offset portion above this central portion about one half 90 of said length. The position of this central portion as well as the length can be varied as desired. In Fig. 4 it is shown as situated approximately in the center of the reed, the structure of the alternate dents 4 and 6 of 95 Fig. 4, being otherwise similar to those of Figs. 1 to 3.

Fig. 5 shows a modification in which the alternate dents 7 and 9 of uniform width are arranged with single offset portions 8 100 and 10 which give a central portion 5 in the same plane, and an offset arrangement to each side of said central portion similar in effect to that of Figs. 1 to 4. These dents 7 and 9 may or may not be duplicates of 105 each other. In the Fig. 6 they are, however, shown as duplicates, the ends of the dents being merely reversed in making up the reed. Obviously the width of the central portion 5 can be varied in this modification 110

the same as with the other forms of the invention already described.

Fig. 7 shows a modification in which the bends or offsets 12 are rounded more than in the preceding figures. This feature can be controlled as desired.

In Fig. 8 the offset portions 13 of the dents are offset less than the width of the individual dents. The clearance provided in this case is less than in the other embodiments shown, but in this embodiment also the friction is less than in the old straight dent reed, for the warp threads do not come in contact with the edges of the dents at the same time, but in succession, thus minimizing the usual shearing action of the straight dent reeds. A section of the reed thus constructed is shown on an enlarged scale in Fig. 11.

In Fig. 9 the reed is made up alternately of dents 14 having narrow central offset portions 16, and dents having wider central offset portions 15, the combined effect being similar to that already described.

The wide range of adaptability of the present invention is obvious to those skilled in the art from the foregoing description, the location and width of the central even portions being controlled as desired.

In the embodiments of the invention shown in Figs. 1 to 6 and 9 to 10, the offset portions of the dent are offset more than the width of the dents, and can be offset more or less as desired, the effective clearance being determined by the amount of this offset. The friction of the warp threads while passing through these offset portions of the reed is correspondingly reduced, and tendency toward fraying, excessive rubbing, and breaking minimized. As a result, softer warp yarns can be used, and yarns with less sizing than heretofore necessary. Also a closer slayed fabric can be produced.

The provision of a central portion of appreciable and variable width is a marked improvement over known reeds having offset dents provided with a central line for packing the filling. The reed does not have to be so carefully adjusted in the loom with respect to the fabric, but uniform driving

of the filling is nevertheless assured the same as in the old straight dent reeds.

The straight dents used in the reed of the present invention may be the old straight dents of the same width as used in the 55 straight dent reeds. The offset dents can be made from wire or strips of the same width, the offset portions being offset at the desired places and for the desired amount.

Variations and modifications can be made 60 in the invention above described without departing from the spirit and scope of the invention as set forth in the following claims.

I claim:

1. A reed made up of an upper and a lower reed frame, dents of uniform width having their end portions in said upper and lower reed frames respectively, and also having central or intermediate portions in the 70 same plane, and with the portions of alternate dents to each side of said central portion offset and arranged in staggered relation.

2. A reed made up of an upper and a 75 lower reed frame, dents of uniform width having their end portions in said upper and lower reed frames respectively, and also having central or intermediate portions in the same plane, and with the portions of alternate dents to each side of said central portion offset a distance greater than the width of the dents, and arranged in staggered relation.

3. A reed made alternately of straight 85 dents, and of offset dents with end and central portions in the same plane as the straight dents and with intermediate offset portions.

4. In a reed a dent of uniform width having central and end portions arranged in 90 the same plane, and intermediate offset portions offset a distance greater than the width of the dents.

In testimony whereof, I affix my signature in the presence of two subscribing witnesses.

E. M. TERRYBERRY.
